Attorneys

UNITED STATES PATENT OFFICE.

SAMUEL DANIELS, OF HARVEY, ILLINOIS, ASSIGNOR OF ONE-HALF TO
JAMES C. REEDER, OF HARVEY, ILLINOIS.

SPRING-GUN.

SPECIFICATION forming part of Letters Patent No. 710,437, dated October 7, 1902.

Application filed October 25, 1901. Serial No. 79,974. (No model.)

To all whom it may concern:

Be it known that I, SAMUEL DANIELS, a citizen of the United States, residing at Harvey, in the county of Cook and State of Illinois, 5 have invented a new and useful Spring-Gun, of which the following is a specification.

This invention relates to spring-guns.

The object is to present a toy pistol composed of a few number of parts, which in operation will be effective for discharging a projectile with considerable force, the projectile to be of such construction as to be harmless in use—that is to say, which will not inflict injury or break articles of glassware should 15 the same be struck thereby.

A further object is to provide a pistol having a novel form of trigger adapted to be set by the cartridge-projecting mechanism when the same is placed in condition to expel the 20 projectile.

A further object is to provide a novel form of operating means for holding the projectile within the barrel of the pistol when the same is being operated to place the actuating-spring 25 at a tension or compression.

With these and other objects in view, as will appear as the nature of the invention is better understood, the same consists in the 30 novel construction and combination of parts of a toy pistol and a projectile therefor, as will be hereinafter fully described and claimed.

In the accompanying drawings, forming a part of this specification, and in which like numerals of reference indicate corresponding 35 parts, there is illustrated one form of embodiment of the invention, together with a slightly-modified form thereof, capable of carrying the same into practical operation, it being understood that the elements therein 40 exhibited may be varied or changed as to shape, proportion, and exact manner of assemblage without departing from the scope of the invention, and in these drawings—

Figure 1 is a view in side elevation, partly 45 in section, of one form of embodiment of the invention, the parts being exhibited in loaded position. Fig. 2 is a perspective detail view, partly broken away, of the barrel shown in Fig. 1. Fig. 3 is a view, similar to Fig. 1, 50 of a modified form of construction. Fig. 4 is a view in rear elevation. Fig. 5 is a similar view in front elevation. Fig. 6 is a view in perspective of the projectile.

Referring to the drawings, 1 designates the stock or handle of the pistol, the same being 55 made of cast metal, in two parts, and held assembled by screws 2, the latter being shown in section in Figs. 1 and 3 and disposed one in the handle portion and one through an extension 3 of the handle, said extension constituting a barrel guide and support. The 60 barrel 4 is mounted for sliding movement between the guides formed by the extensions 3, the latter being disposed partially to inclose the barrel by inward-curved extensions 5, as 65 clearly shown in Fig. 5, and by two curved lugs or bosses 6, disposed at the top of the handle, as clearly shown in Figs. 1, 3, and 4. The barrel is provided near its rear end and in horizontal alinement with two slots 7, 70 through which passes a screw or pin 8, which serves the triple function of a means for limiting the longitudinal movement of the barrel, a pivot for the trigger 9, and an abutment or stop for the actuating-spring 75 10, in addition to which it also serves to hold the sections of the handle more securely assembled. The trigger 9 is provided with the usual finger-piece 10^a and with a dog 11, provided at its front end with a barb 12 to 80 engage the projectile 13 and hold the same within the barrel against the pressure of the spring 10, as clearly shown in Fig. 1. The rear portion of the trigger adjacent to the pivot 8 is provided with a shoulder 14, against 85 which the actuating-spring bears, whereby upon the compression of the spring the barbed end of the trigger will be thrown upward, thus to engage and hold the projectile in the barrel, as will presently appear. The under 90 side of the barrel is provided with a longitudinal slot 15, in which the finger-piece of the trigger works, thereby to permit the barrel to be pushed rearward in the handle, as indicated by dotted lines in Fig. 3. 95

In the form of pistol shown in Fig. 1 the projectile is held against the spring by the thumb of the operator, and this operates successfully where the barrel is of short length, as shown in Fig. 1; but where the barrel is 100 of considerable length, as shown in Fig. 3, an automatically-operating means is provided for engaging the projectile to hold it seated against the spring, while the barrel is being pushed backward to place the spring under 105 compression. The means comprises a spring-

arm 16, one end of which is secured to the under side of the barrel, as by a rivet 17 or by being soldered thereto, the outer end of the arm being bent at an angle to its length 5 to present a toe 18, adapted to project through an orifice 19 in the barrel and in front of the projectile, as will be understood by reference to Fig. 3. The upper surface of the extension 3 is provided with a recess 20, in which 10 the arm 16 moves when the barrel is pushed backward, the outer end of the extension being beveled or inclined at 21 to ride against the said arm, and thus force the toe into the orifice 19. The trigger mechanism in the form 15 of pistol shown in Fig. 3 is the same as that shown in Fig. 1, and in both instances the employment of a trigger-spring is rendered unnecessary, as the actuating-spring 10, by contact with the shoulder 14, serves to throw 20 the trigger in the proper direction to cause it to engage with the projectile. By dispensing with the employment of the trigger-spring the cost of production of the pistol is reduced and liability of derangement in use cor- 25 respondingly reduced, the operating-spring 10 effecting actuation of the trigger in a positive and thoroughly efficient manner. It will be obvious that, if desired, a trigger-spring may be employed, and as its manner of ap- 30 plication to position and the mode of its operation will be obvious illustration is deemed unnecessary.

The projectile 13, to which reference has been made, comprises a hollow metallic shell 35 22, preferably of the same diameter throughout its length and having its butt provided with an orifice 23 and an inwardly-extending annular flange 23^a to be engaged by the barb 12 of the dog 11, the front of the shell being 40 contracted, as at 24, to engage and secure a tip 25, constructed, preferably, of rubber or some other yielding substance. The manner herein shown of assembling the tip with the shell will be found thoroughly effective in 45 use; but it is to be understood that the invention is not to be limited to this precise manner of arrangement, as the parts may be otherwise assembled, as by being cemented together or having a pin passed through the 50 shell and the tip, without departing from the invention, and as this will be obvious and is well known detailed illustration is deemed unnecessary.

In loading the pistol shown in Fig. 1 the 55 projectile is slipped into the barrel and will rest upon the front coil of the spring 10, as shown in Fig. 3. The thumb of the operator is then placed over the end of the muzzle and the barrel pushed backward, the tip of the 60 projectile bearing against the thumb and the butt compressing the spring. As the spring is compressed its rear coil by contact with the shoulder 14 throws the dog 11 upward, so that when the flange of the orifice 23 of the 65 shell contacts with the barb the dog will first be depressed and again thrown upward, when

the shoulder of the barb clears the flange of the orifice, whereupon the projectile will be locked in the barrel. To release the projectile, it will only be necessary to pull the 70 trigger in the usual manner. The tip being of rubber, as before stated, will render it harmless, so that the toy may be used indoors with impunity and without any danger of injury either to individuals or to glassware. 75

In loading the form of pistol shown in Fig. 3 the projectile is slipped into the barrel and as the barrel is pushed rearward the toe of the arm 16 is forced in front of the tip, and thus holds the projectile against the spring 80 in the same manner as the thumb of the operator does in loading the form of pistol shown in Fig. 1. In both cases after the projectile has been engaged by the barb of the dog the barrel is drawn forward to its normal 85 position and is stopped when it reaches the same by coaction between the pin 8 and the rear wall of the slot 7.

The device of this invention is exceedingly simple of construction and may therefore be 90 constructed and sold at a low figure, and by reason of the fact that it will be safe in use it will recommend itself to parents desiring to provide their children with a toy pistol adapted for target practice. 95

Having thus fully described my invention, what I claim as new, and desire to secure by Letters Patent, is—

1. A toy pistol comprising a handle, a barrel mounted for sliding movement thereon, a 100 spring housed in the barrel, and a trigger provided with means for engaging and holding the projectile against the stress of the spring, the trigger being brought to operative position with relation to the projectile by the compression of the spring.

2. A toy pistol comprising a handle supporting a slideable barrel, a trigger provided with a barb and with a shoulder, and a projectile-actuating spring housed within the barrel and bearing at its rear end against the shoulder, substantially as and for the purpose specified.

3. A toy pistol comprising a handle, a barrel supported for sliding movement thereon, a 115 trigger provided with a projectile-engaging barb, a projectile-actuating spring housed within the barrel and bearing at its rear end against the trigger to move the same into proper position to engage the projectile, and 120 projectile-engaging means carried by the barrel and brought into operative relation with the projectile when the barrel is moved to compress the spring.

In testimony that I claim the foregoing as 125 my own I have hereto affixed my signature in the presence of two witnesses.

SAMUEL DANIELS.
